(57) CLAIM

The ornamental design for a cheese board set, as shown and described.

DESCRIPTION

FIG. 1 is a perspective view of a cheese board set showing my new design in retracted form,

FIG. 2 is a perspective view thereof, in extended form,

FIG. 3 is a perspective view thereof, in extended form with parts removed,

FIG. 4 is a front view thereof,

FIG. 5 is a back view thereof,

FIG. 6 is a right-side view thereof,

FIG. 7 is a left-side view thereof,

FIG. 8 is a top view thereof; and,

FIG. 9 is a bottom view thereof.

The broken lines shown in the drawings are included for the purpose of illustrating environmental structure and form no part of the claimed design.
